UNITED STATES PATENT OFFICE.

JOHN GERMAINE CARNEY AND FRANK JOSEPH WAGNER, OF ERIE, PENNSYLVANIA.

FLUID-METER.

1,187,607.

Specification of Letters Patent. Patented June 20, 1916.

Application filed May 13, 1915. Serial No. 27,914.

To all whom it may concern:

Be it known that we, JOHN G. CARNEY and FRANK J. WAGNER, citizens of the United States, residing at Erie, in the county of Erie, State of Pennsylvania, have invented a new and useful Fluid-Meter, of which the following is a specification.

The present invention appertains to meters, and aims to provide a novel and improved meter whereby the amount of gas, air or other fluid flowing through a pipe may be determined and recorded with approximate accuracy.

The object of the invention is the provision of a device adapted to be interposed in the fluid pipe or conduit, and which is so constructed and operable, that the fluid in flowing through the pipe or conduit will operate the indicating or recording device according to the volume of fluid flowing through the pipe, and the pressure and velocity thereof.

It is also within the scope of the invention to provide a fluid meter which is comparatively simple and inexpensive in construction, which employs but few parts, which operates with little friction, and which operates in a thoroughly practical, simple and efficient manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

The invention is illustrated in its preferred embodiment in the accompanying drawing, wherein:—

Figure 1 is a vertical section of the meter. Fig. 2 is a horizontal section taken on the line 2—2 of Fig. 1.

In carrying out the invention there is provided a valve casing 1 adapted to be readily interposed in the fluid pipe or conduit, and having a partition 2 therein between its ends, and an upwardly projecting branch 3 provided with an outturned annular flange 4. The partition 2 is provided with an opening 5, which is tapered, the edges of the opening 5 being beveled to provide a beveled valve seat. The opening 5 and branch 3 are in alinement.

A sleeve 6 having an annular outturned flange 7 at one end is attached to the branch 3, the flange 7 being bolted or otherwise secured to the flange 4, and a disk or partition 8 is clamped between the flanges 4 and 7 of the branch 3 and sleeve 6, respectively, to close the passage between the branch 3 and sleeve 6.

A stem 9 is slidable through the disk 8, and an inverted conical valve 10 is threaded or otherwise engaged to the lower or inner end of the stem 9, and cooperates with the valve seat formed by the opening 5. The valve 10 is movable into the opening 5 to seat snugly therein with the apex or point of the valve projecting beyond the lower surface of the partition 2.

The disk 8 is provided adjacent its margin with a pair of upwardly projecting inclined standards or brackets 11, and a gear wheel 12 is journaled between the upper or free ends of the standards 11 and intermeshes with a rack 13 formed upon the upper end portion of the stem 9 above the disk 8. A second and larger gear wheel 14 is carried by a shaft 14^a between the standards 11 below the gear wheel 12 and intermeshes with the said gear wheel 12, and the shaft 14^a projects out through one side of the sleeve 6 and carries at its outer end, an upwardly projecting arm 15. The upper or free end of the arm 15 carries a pen or marking element 16 which bears against a flat circular chart 17 carried rotatably by an ordinary recording gage 18, in order that the vertical chart 17 will be rotated by means of a suitable clockwork.

A cap or cover plate 19 is bolted or otherwise detachably secured upon the upper end of the sleeve 6, and the recording gage 18 is carried by the plate 19. The chart 17 is provided with concentric rings 21 which may be suitably graduated to indicate the volume of fluid under various pressures, or the like, the chart 17 has lines 22 intersecting the lines 21 and which may be graduated by suitable units of time, according to the velocity at which the chart 17 is rotated by the clockwork (not shown).

In operation, supposing the casing 1 to be interposed in a fluid pipe or conduit, so that the fluid flows from the left to the right, as seen in Fig. 1, the fluid in passing through the casing 1 will raise the valve 10, and the stem 9 will thus be raised to carry the rack 13 therewith. The rack 13 in engaging the

gear wheel 12 will rotate the said gear wheel and thus will impart rotation to the gear wheel 14, whereby the indicating or recording arm 15 is oscillated. When the 5 pressure or velocity of the fluid is great, the valve 10 will be raised to a considerable distance, whereas when the pressure is low, the valve 10 will drop close to its seat. Consequently, the valve 10 will be raised proportionately to the pressure or velocity of the 10 fluid, and the pen or marking element 16 will inscribe a line 23 upon the chart 17 which will indicate upon the chart the approximate volume of fluid flowing through 15 the pipe at the various periods of time. From this line 23 the volume of fluid which has passed through the pipe for a given time may be determined with considerable accuracy.

20 Due to the provision of the conical valve 10 and the beveled valve seat 5, the device will operate in a thoroughly efficient manner under various pressures of the fluid and the valve 10 will be lifted properly under 25 various conditions. The present device thus provides a pressure and volumetric meter of simple, yet effective operation. It will be noted that the arm 15 may be employed as an indicator or pointer, or may be employed 30 for carrying one or more marking elements for coöperation with one or more charts according to the nature of measurements desired. The valve 10 is sufficiently heavy, or acts as a weight, whereby it will 35 move against the fluid flowing through the opening 5, as will be apparent, and it will also be noted that the disk or partition 8 prevents the fluid from escaping. The

gearing is confined within the sleeve 6 to be housed thereby, and the several parts of 40 the structure may be readily separated and assembled.

The other advantages and capabilities of the present invention will be obvious to those skilled in the art, without further comment being necessary.

Having thus described the invention, what is claimed as new is:—

In a fluid meter, a casing having a partition therein and a branch, the partition 50 having an opening in alinement with the branch, a sleeve secured to the branch, a disk clamped between the branch and sleeve and having a bracket, a stem slideable through the disk, a conical valve carried 55 by the stem and movable into said opening to seat therein, a cover secured to the sleeve, a shaft projecting through one side of the sleeve and journaled to said bracket, an indicating arm carried by the outer end of 60 said shaft, the stem having a rack within the sleeve, gearing carried by said bracket and connecting said rack and shaft and a rotatable flat vertical chart mounted upon the said cover and adapted to be clock 65 driven, the free end of said arm having a marking element coöperable with said chart.

In testimony that we claim the foregoing as our own, we have hereto affixed our signatures in the presence of two witnesses. 70
